ATTORNEYS.

UNITED STATES PATENT OFFICE.

EARL C. BOOTH, OF INDIANAPOLIS, INDIANA, ASSIGNOR TO HOLCOMB & HOKE MANUFACTURING COMPANY, OF INDIANAPOLIS, INDIANA, A CORPORATION.

DESIGN FOR A STERILIZING-CABINET.

54,829.

Specification for Design.

Patented Apr. 13, 1920.

Application filed December 13, 1919. Serial No. 344,704. Term of patent 14 years.

To all whom it may concern:

Be it known that I, EARL C. Booth, a citizen of the United States of America, residing in the city of Indianapolis, county of Marion, and State of Indiana, have invented a new and original and ornamental Design for a Sterilizing-Cabinet, of which the following is a specification, reference be-

ing had to the accompanying drawings, forming a part thereof.

In the drawing is shown a perspective view of the sterilizing cabinet.

I claim:—

The ornamental design for a sterilizing cabinet, as shown.

EARL C. BOOTH.
